UNITED STATES PATENT OFFICE.

JAMES D. TEW, OF HUDSON, OHIO, ASSIGNOR TO THE B. F. GOODRICH COMPANY, OF NEW YORK, N. Y., A CORPORATION OF NEW YORK.

DESIGN FOR A PNEUMATIC TIRE.

Application filed December 14, 1922. Serial No. 4,592. Term of patent 14 years.

To all whom it may concern:

Be it known that I, JAMES D. TEW, a citizen of the United States, residing at Hudson, in the county of Summit and State of Ohio, have invented a new, original, and ornamental Design for Pneumatic Tires, of which the following is a specification, reference being had to the accompanying drawing, forming a part thereof.

Fig. 1 is a plan view of a pneumatic tire casing showing my design.

Fig. 2 is a cross-section on the line 2—2 of Fig. 1, omitting internal structural details.

I claim:

The ornamental design for a pneumatic tire as shown.

JAMES D. TEW.
